US00D592223S

(12) **United States Design Patent**
Neuhaus

(10) **Patent No.:** US D592,223 S
(45) **Date of Patent:** ** May 12, 2009

(54) **PRINTED MATERIAL AND ICON FOR COMPUTER DISPLAY, ELECTRONIC SCREEN**

(75) Inventor: **Hans-Jorg Peter Neuhaus**, Solothurn (CH)

(73) Assignee: **Bystronic Laser AG**, Niederenz (CH)

(**) Term: **14 Years**

(21) Appl. No.: **29/278,757**

(22) Filed: **Apr. 9, 2007**

Related U.S. Application Data

(62) Division of application No. 29/278,700, filed on Apr. 6, 2007, now Pat. No. Des. 582,427.

(30) **Foreign Application Priority Data**

Oct. 12, 2006 (CH) 133302

(51) **LOC (9) Cl.** 32-00

(52) **U.S. Cl.** D14/491

(57) **CLAIM**

The ornamental design for printed material and icon for computer display, electronic screen, as shown and described.

DESCRIPTION

FIG. 1 is a plan view of an icon according to an embodiment of my new design, as shown in the environment of a computer display or electronic screen; and,

FIG. 2 is a plan view of another embodiment of my new design showing a printed material.

The broken lines shown herein are for the purpose of illustrating environmental structure and form no part of the claimed design. The broken line of FIG. 1 shows a portion of a computer display or electronic screen. The broken line of FIG. 2 shows a portion of a printed material.
